(57) **CLAIM**

The ornamental design for a cable positioning device, as shown and described.

DESCRIPTION

FIG. 1 is a top perspective view of a cable positioning device;

FIG. 2 is a bottom perspective view of the cable positioning device of FIG. 1;

FIG. 3 is a front view of the cable positioning device of FIG. 1;

FIG. 4 is a back view of the cable positioning device of FIG. 1;

FIG. 5 is a left side view of the cable positioning device of FIG. 1;

FIG. 6 is a right side view of the cable positioning device of FIG. 1;

FIG. 7 is a top view of the cable positioning device of FIG. 1; and,

FIG. 8 is a bottom view of the cable positioning device of FIG. 1.

The cable positioning device can include a hook portion, connected to a horizontally extending portion. A vertical portion can extend downward from the horizontal portion and support a cable saddle. In an example, the cable saddle can be rectangular in shape.

The dash-dash broken lines shown in all of the drawing figures are for illustrative purposes only and form no part of the claimed design. The dash-dot broken lines represent boundary lines that form no part of the claimed design.
